No. 11,434

September 23, 1879

UNITED STATES PATENT OFFICE.

LE ROY W. FAIRCHILD, OF NEW YORK, N. Y.

DESIGN FOR PENCIL-CASES.

Specification forming part of Design No. **11,434**, dated September 23, 1879; application filed August 16, 1879.
[Term of patent 7 years.]

To all whom it may concern:

Be it known that I, LE ROY W. FAIRCHILD, of the city, county, and State of New York, have produced a new and original Design for Ornamental Pencil or other Small Implement Cases, of which the following is a full, clear, and exact description, reference being had to the accompanying photographic illustration, making part of this specification.

The design consists in the main of the representation, upon the external shell of a pencil or other small implement case, of a cap and a whip, significant of a jockey.

A represents the case with its ornamentation entire. b is the ring, secured to the closed end of the case in the ordinary manner at c.

d d' are the jockey-cap and whip, which are formed upon the case about midway between the two end beads e and f. The different parts may be shown in metals or other materials of various colors, if desired.

What I claim as my invention is—

A design for a pencil or other small implement case, consisting of the tube or shell, jockey-cap d, whip d', beads e and f, ring b, and eye c, substantially as shown and described.

LE ROY W. FAIRCHILD.
